UNITED STATES PATENT OFFICE.

GEORGE H. BARKER, OF LOS ANGELES, CALIFORNIA.

GAME-COUNTER.

1,168,374.

Specification of Letters Patent.

Patented Jan. 18, 1916.

Application filed October 30, 1911, Serial No. 657,433. Renewed July 12, 1915. Serial No. 39,522.

To all whom it may concern:

Be it known that I, GEORGE H. BARKER, a citizen of the United States, and resident of Los Angeles, county of Los Angeles, and 5 State of California, have invented certain new and useful Improvements in Game-Counters, of which the following is a specification.

My invention relates to game counters 10 and has particular reference to a counter for use in the game of cribbage. The counters heretofore used in connection with the game of cribbage have usually consisted of a board provided with four parallel rows of 15 holes, each of two players using half of the board. There are ordinarily thirty holes in each row and as the game consists of one hundred and twenty points, it has been necessary to count over the rows twice. This 20 occasions confusion as the players may not remember whether they are on the first or last turn in the count. To avoid this it would, of course, be possible to construct a board with one hundred and twenty holes 25 for each player but this would make a board of awkward size and would necessitate a considerable reach to the extremities of the board. Furthermore in counting on the parallel rows the players sometime become 30 confused as to the direction in which they are counting on the particular row for the reason that on the lower row they count toward the left and on the upper row toward the right.

One of the objects of my invention is the 35 construction of a board having holes or recesses for the counting pegs, the holes being arranged so that the player always counts in one direction and without retracing his 40 steps or using the same holes twice in one game. Thus I accomplish by arranging the holes in the form of a spiral, the player preferably beginning at the outside spiral and ending the game with the central opening. By thus arranging the board it will 45 be seen that space is economized; that instead of arranging the board for two players, each player may be given a small individual board and that therefore the number 50 of players is not limited; that the count is always in one direction; that direction being preferably clockwise and that the count-

ing holes are arranged more compactly thus obviating the reach necessary in many of the present boards.

55 My invention will be more readily understood by reference to the accompanying drawings, wherein,

Figure 1 is a plan view of an individual game counter arranged in accordance with 60 my invention; Fig. 2 is a section on the line 2—2 of Fig. 1; Fig. 3 illustrates a modification of the construction of Fig. 1, wherein the board is rectangular and the holes arranged accordingly although still in the 65 same generally spiral outline; Fig. 4 is a still further modification in shape, the outline in this case being octagonal, and Fig. 5 is a still further modification showing the 70 construction of Fig. 1 as applied to a single board for two players.

Referring more particularly to the drawings it will be seen that the base or board 10, which may be of any preferred construction, is provided with a plurality of holes 75 11, these holes being arranged in spiral form. In counting it will, of course, be understood that pegs are used, which pegs are fitted into the holes 11. Preferably I provide also a number of additional perforations 12, in which the extra pegs may be 80 kept and in which the score of the complete games may also be kept.

Referring to Fig. 3 it will be seen that the board 13 is square and that the perforations 85 14, while following the outline of the board, are arranged in generally spiral outline.

In Fig. 4 I have shown an octagonal board 15, and likewise the holes 16, while following the outline of the board, still follow 90 their generally spiral path.

In Fig. 5, I provide a board 17, on which are arranged two sets of counting holes, the 95 holes being arranged exactly as shown in Fig. 1.

While I have shown my game counter as formed from a simple board with holes therein, it will be understood that the board itself may be modified in many ways, that is, I may provide a recess having a cover 100 within which spare pegs may be kept; also I may provide other counting devices than the pegs or I may provide a hollow base having a cap with the necessary perfora-

tions therein; also that other and further modifications may be made all without departing from the spirit of my invention.

I claim:

- 5 A game counter composed of a base having a line of counting recesses therein, said line being arranged substantially in the

form of a spiral, said spiral extending in a continuous line from the center to the outer edge of the base, substantially as described. 10

GEORGE H. BARKER.
